BUILDING CONSTRUCTION

Raymond M. Calkins, Deerfield, and James W. Swank, Chicago, Ill.

Application April 29, 1935, Serial No. 18,798

2 Claims. (CL. 189—86)

Our invention relates to building construction of the type involving panels of sheet metal or other suitable material, and it is the object of our invention to provide a new and improved form and arrangement of parts by the use of which an improved wall or ceiling structure may be produced. It is one of the objects of our invention to provide an improved arrangement of parts by the use of which a tiled facing may be added to a wall or ceiling or by which such facing parts may form the body of a wall in a manner to provide a paneled effect, or for improving the acoustical properties of a room, or for any other purpose.

It is one of the objects of our invention to provide an improved arrangement of this type by reason of which the work of applying the panels in operative position may be substantially cut down as compared with other structures employed for similar purposes. To this end, it is one of the objects of our invention to provide an improved arrangement in which one edge of a panel is tacked in position and the adjacent edge of the adjacent panel is capable of being forced into locking engagement with the tacked edge portion, the locking of the two panels being effected preferably by a resilient snap engagement of one panel with the other, and the arrangement being such that the panels are afforded very strong and rigid support by means covered and hidden by the body portions of the panels.

It is another object of our invention to provide an arrangement of this sort in which adjacent panels are connected together by the use of interfitting boxes arranged along the edges of the panels, with the parts so disposed that the inside box of one panel can be pushed backwardly into operative position within the outside box of the adjacent panel where it is held by snap engagement therewith, the boxes being arranged so that there shall be a camming action by which the movement of the boxes into interfitting relationship may be readily effected, and each two interfitting boxes being connected with the body portions of the panels by flange portions extending straight backwardly from the edge portions of the bodies in face contact with each other.

It is another object of our invention to improve constructions of this type in sundry details hereinafter pointed out. The preferred means by which we have accomplished our several objects are illustrated in the accompanying drawing and are hereinafter specifically described. That which we believe to be new and

desire to cover by Letters Patent is set forth in the claims.

In the drawing.—

Fig. 1 is a horizontal cross sectional view through a fragmentary portion of a ceiling provided with our improved facing means;

Fig. 2 is a face view of a portion of the ceiling shown in Fig. 1;

Fig. 3 is a view similar to a portion of Fig. 1 but showing the parts in a preliminary relative position in the course of the installation of a wall facing; and

Fig. 4 is a vertical sectional view through a fragmentary portion of a side wall in which our improved facing means forms the body of the wall.

Referring now to Figs. 1, 2, and 3 in which corresponding parts are indicated by the same reference characters, 10 indicates a ceiling of any approved type having a series of furring strips 11 secured thereon by any suitable means in parallel relation to each other, in the arrangement shown being spaced at a distance of about twelve inches between centers. Upon the bottom faces of the furring strips 11 we have provided a series of panels 12 formed of sheet metal, such panels being secured in position by means of box structures as hereinafter set forth. In the arrangement shown, the panels are employed as acoustical tile, being provided with openings 13 therethrough in spaced relation throughout their face portions. Upon their inner or upper faces, each of the panels is provided with a layer 14 of insulating or sound absorbent material which in the arrangement shown is in the form of rock wool. As will be readily appreciated, by the use of the panels of metal with the openings therethrough and with such openings leading to a substantial layer of insulating material as described, very satisfactory acoustical effects are assured. The outside or bottom faces of the panels are preferably covered with enamel, or may be given any other desirable ornamental finish.

The means illustrated for securing the panels together and for holding them in position upon the furring strips 11 comprise interfitting box structures formed of flanges bent into cooperating relation along the side edges of the panels. Each two interfitting boxes comprises an inside box formed of a series of flanges 15, 16, 17 and 18 at one edge of one panel and an outside box comprising a series of flanges 19, 20, 21, 22 and 23 formed on the adjacent edge of the connected panel. In the arrangement shown, the flanges 55

22 of the outside boxes are comparatively narrow and are directed forwardly and inwardly with respect to the box, terminating at their inner edges in flanges 23 which are directed forwardly and outwardly, the flanges 22 and 23 extending only a short distance transversely of the box so as to leave the box open substantially across the front. The flange 17 of the inside box is arranged in forwardly divergent position with respect to the flange 15, the flange 18 at the front edge of the flange 17 being directed forwardly and inwardly with respect to the box. As is clearly shown in Fig. 3, the arrangement is such that when the inside box of one panel is presented from the front to the outside box of an adjacent panel the parts are movable readily into engagement with each other so that upon a backward pressure on the panel equipped with the inside box a camming action takes place for spreading the outside box and contracting the inside box sufficiently against the resiliency of the parts for permitting the boxes to be pressed into cooperative relation as shown in Fig. 1. As will be readily understood, as soon as the flange 17 passes the edge of flange 22, the parts snap into holding engagement.

In the use of our improved panel construction, the outside box of a panel is secured in position upon the face of a furring strip 14 by means of a nail 24 or in any other suitable manner. The inside box of an adjacent panel is then presented in the relation as shown in Fig. 3 and is pushed back into interfitting relationship with the outside box, whereupon the outside box at the opposite edge of the panel being installed is tacked or otherwise secured in position, the installation of the facing for a wall being thus effected very easily and quickly.

In the arrangement shown in Fig. 4, our improved panel construction is employed for providing a side wall, the panels themselves comprising the body of the wall. In this arrangement, a series of strips 25 are secured in parallel spaced relation across the faces of a series of studs 26. In such construction, insulating boards 27 are secured to the panels 28 in lieu of the rock wool insulation as shown in Fig. 1, but any desired form of insulating means may be used. Inasmuch as the arrangement of the boxes is the same in Fig. 4 as is above described in connection with Fig. 1, the same reference characters have been employed and it is believed to be unnecessary to describe the construction further. It will be noted that the panels 28 are not perforated in the arrangement shown, but the panels may be arranged as desired with respect to the form or design of the exterior face.

We have found that a very satisfactory construction of this type may be provided by the use of comparatively thin sheet metal, an effective facing being provided by the use of metal as thin as twenty-four gauge. Any type of insulating material as desired may be employed, either secured to the face of the panel or merely resting thereon as shown in Fig. 1 of the drawing. The panels may be employed for either outside wall facings or inside wall facings, being easily and readily applied in operative position in any case without the use of special tools.

While we prefer to employ the form and arrangement as shown in our drawing and as above described, it is to be understood that our invention is not limited to this arrangement except so far as the claims may be so limited by the prior art.

We claim:—

1. In a building construction, the combination of a sheet metal panel having a straight flange portion extending backwardly from one edge of the body portion of the panel at right angles thereto and having a box structure formed on the inner face of the flange and comprising a second flange portion at right angles to said first named flange portion, and a third flange portion extending forwardly in divergent position with respect to said first named flange portion, and a second sheet metal panel having a fourth flange portion extending straight backwardly from its edge at right angles thereto and having a box structure formed on the outer face of the flange in position to be nailed to a supporting member, and comprising a fifth flange portion at right angles to said fourth flange portion, a sixth flange portion extending forwardly from said fifth flange portion in position to permit the first named box structure to enter the second box structure by a camming action from the front, and means on the forward edge of said sixth flange portion adapted by snap engagement with said third flange portion to hold said two box structures releasably together for connecting said panels side by side and supporting them from said supporting member in forwardly spaced relation thereto.

2. In a building construction, the combination of a sheet metal panel having a straight flange portion extending backwardly from one edge of the body portion of the panel at right angles thereto and having a box structure formed on the inner face of the flange and comprising a second flange portion at right angles to said first named flange portion, and a third flange portion extending forwardly in divergent position with respect to said first named flange portion, and a second sheet metal panel having a fourth flange portion extending straight backwardly from its edge at right angles thereto and having a box structure formed on the outer face of the flange in position to be nailed to a supporting member, and comprising a fifth flange portion at right angles to said fourth flange portion, a sixth flange portion extending forwardly from said fifth flange portion in divergent position with respect to said fourth flange portion in such spaced relation thereto as to permit the first named box structure to enter the second box structure by a camming action from the front, and a seventh flange portion on the forward edge of said sixth flange portion extending forwardly in convergent position with respect to said fourth flange portion and adapted by snap engagement with said third flange portion to hold said two box structures releasably together for connecting said panels side by side and supporting them from said supporting member in forwardly spaced relation thereto.
